FENCE POST

Filed Sept. 24, 1928

Julius T. Bergan, INVENTOR
BY Victor J. Evans

ATTORNEY

UNITED STATES PATENT OFFICE

JULIUS T. BERGAN, OF HARMONY, MINNESOTA

FENCE POST

Application filed September 24, 1928. Serial No. 308,097.

This invention relates to a fence post, the general object of the invention being to form the post with a ground or post section and a fence carrying section which is slidably mounted on the post section, with latch means for holding the fence section in adjusted position on the post section, whereby the fence section can be adjusted to raise and lower the fence to adjust the same in relation to the ground.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a view showing the improved post in use.

Figure 2 is an edge view of the post.

Figure 3 is an elevation of the post.

Figure 4 is a section on line 4—4 of Figure 3.

In these views, the numeral 1 indicates the post or ground section and 2 indicates the fence carrying section which is slidably mounted on the section 1, the section 2 having its part to which the fence, shown at A in Figure 1, is attached, projecting beyond the section 1 so that the fence will not interfere with the movement of the section 2 on the section 1. The drawing shows the two sections of channel shape in cross section with the flanges of the section 2 extending beyond the flanges of the section 1 and with the flanges of the section 2 provided with notches 3 for receiving the wires of the fence A, these wires being held in the notches by the short wires 4 which extend around the closed sides of the section 2 and have their ends twisted around the fence wires, as clearly shown in Figure 1. Thus by moving the section 2, the fence will also be moved so that it can be adjusted in relation to the ground. A pair of substantially U-shaped members 5 engage the flanges of the two sections and the outer projecting

parts of these U-shaped members are connected together by a pin or bolt 6 which also passes through an eye part formed on a spring strip 7 so that this strip is hingedly connected with the members 5. A bar 8 is carried by the free end of the strip 7 and has a bent part which is adapted to engage a flange of the section 2 so as to hold the strip 7 under tension and thus cause said strip and the members 5 to lock the section 2 to the section 1. By moving the bar 8 out of engagement with the flange of section 2, the pressure is released so that the section 2 can be moved on the section 1. As will be seen, the spring strip 7 is so constructed and arranged that its lower part will rest against the section 2, while its upper part is spaced from said section. Thus when the strip 7 is pressed inwardly by placing the bar 8 over the edge of a flange of the section 2, the strip 7 is placed under tension so that its lower part will bear against a part of the section 2 with considerable pressure and the members 5 are also caused to bear against the section 1 so that the two sections are pressed together and thus frictionally held in adjusted position.

From the foregoing it will be seen that the fence can be raised or lowered by moving the section 2 on the section 1 and by raising the fence to space its bottom wire from the ground, grass, weeds and the like growing at the bottom of the fence can be cut or stock can be permitted to eat this material. Also the fence can be raised to permit small stock, such as pigs, to pass under the fence so that in this case, the device could be used as a gate.

The invention is also useful in connection with snow fences where it is necessary to raise the fence to keep it above the level of the snow. Of course, the invention is useful in other situations.

The section 1 is provided with the usual anchor 9 for rigidly holding the same in the ground.

It is thought from the foregoing description that the advantages and novel features of the invention will be readily apparent.

It is to be understood that changes may be made in the construction and in the combination and arrangement of the several parts,

provided that such changes fall within the scope of the appended claim.

What I claim is:—

A fence post comprising a post section and a fence carrying section slidably arranged on the post section, each section being of channel shape in cross section with the flanges of the fence carrying section extending beyond the flanges of the post section the edges of the flanges of the fence carrying sections having notches therein for receiving the fence wires, means for connecting the fence wires to the edges of the flanges of the fence carrying section, a pair of U-shaped members engaging the flanges of both sections, with one limb of each member extending beyond the rear of the fence carrying section, a spring strip pivoted to the extended ends of the U-shaped members and a hook member connected with the free end of the spring strip and adapted to be placed over a flange of the fence carrying section to place the strip under tension and thus frictionally hold the two sections together.

25 In testimony whereof I affix my signature.
JULIUS T. BERGAN.
